DESIGN FOR A VACUUM CLEANER

Lars Johan Faith Ell, Stockholm, Sweden, assignor to Electrolux Corporation, Dover, Del., a corporation of Delaware

Application January 19, 1939, Serial No. 82,440
In Czechoslovakia November 19, 1938

Term of patent 14 years

To all whom it may concern:

Be it known that I, Lars Johan Faith Ell, a subject of the King of Sweden, residing at Stockholm, Sweden, have invented a new, original, and ornamental Design for a Vacuum Cleaner, of which the following is a specification, reference being had to the accompanying drawing, forming a part thereof and of which:

Fig. 1 is a perspective view showing the top,

one side and one end of a vacuum cleaner embodying my new design; and

Fig. 2 is a perspective view showing the top, opposite side and other end of the vacuum cleaner illustrated in Fig. 1.

I claim:

The ornamental design for a vacuum cleaner, as shown.

LARS JOHAN FAITH ELL.
